UNITED STATES PATENT OFFICE.

CHARLES VIVION STUART, OF MEMPHIS, TENNESSEE.

BURNER.

1,112,234.

Specification of Letters Patent. Patented Sept. 29, 1914.

Application filed March 24, 1914. Serial No. 826,991.

To all whom it may concern:

Be it known that I, CHARLES V. STUART, a citizen of the United States, residing at Memphis, in the county of Shelby and State of Tennessee, have invented new and useful Improvements in Burners, of which the following is a specification.

The invention relates to an improved burner designed primarily for use with solid fuel, the construction providing for the initial use of a liquid fuel to produce an incandescence in the combustion chamber, wherein the solid fuel may be completely burned with the maximum heating effect and minimum resultant products of combustion.

The main object of the present invention is the provision of a burner involving a combustion chamber to which a liquid fuel is introduced under pressure and burned to produce a state of incandescence in said chamber, a solid fuel being introduced into said chamber under pressure and under mechanical control to distribute said fuel within the chamber to provide for the complete combustion of the fuel.

The invention in the preferred form of details will be described in the following specification, reference being had particularly to the accompanying drawings, in which the figure is a vertical sectional view partly in elevation of the improved burner.

The improved burner, as is clearly illustrated in the accompanying drawing, comprises a combustion chamber 1, which may be of any desired size or contour in accordance with the work contemplated. In the form illustrated, the chamber comprises a suitable casing, interiorly lined with fire brick or other refractory material, as 2, one end of the chamber being open as at 3, from which the heated products are taken for use.

The opposing or relatively closed end of the chamber has secured thereto one terminal of a conduit 4, providing, as hereinafter described, for the delivery of the fuel for combustion to the chamber 1. The remote end of the conduit is open to the atmosphere, for the admission of air, and adjacent said open end the conduit is provided with any desired type of suction pressure device, as 5. This device is shown in the drawings as of the injector form, though it is to be understood that I contemplate the use of any desired type of such device, so long as in its use it will create a pressure in advance

of the same toward the combustion chamber, and a suction in rear of the same toward the open end of the conduit.

In the conduit 4 immediately adjacent the combustion chamber, is arranged an interrupter 6, in the form of a baffle means. As shown, such interrupter is in the form of a spiral element compelling a rotative movement of such material as is forced by the same toward the combustion chamber. It is of course to be understood that while preferring such spiral baffle element, I contemplate the use of any desired type of such baffle device as may be found desirable in the particular instance.

Intermediate the pressure device 5 and the baffle 6 the conduit 4 is in communication with a laterally projected feed pipe 7, terminating in a hopper 8. The hopper and feed pipe are constructed for the feeding of the solid fuel to the conduit 4, and for such feeding purposes, as well as for an additional function, which will later appear, I arrange in the conduit and feed pipe a spiral conveyor 9, positively driven through suitable mechanism as 10. The delivery end of the conveyor terminates in the feed pipe 7 beyond the juncture of said pipe with the conduit, for a purpose which will presently appear.

The conduit 4 is in open communication with the chamber 1 through an opening 11, the walls of which converge from the conduit to the casing, the said opening 11 constituting what may be termed the burner opening, with the point of ignition at the combustion chamber end of such opening.

In use, in the type of burner shown, the conduit 4 is in open communication with a liquid fuel pipe 12, having a controlling valve, and arranged intermediate the pressure element 5 and the open end of the conduit. The fuel pipe is preferably for the delivery of a suitable hydro-carbon, though I do not limit myself in any particular to the use of such.

In the use of the improved burner, the liquid fuel pipe 12 is open to the conduit 4 so that a previously determined quantity of the liquid fuel is delivered to the conduit, and by the suction of the pressure element 5 mixed with the indrawn air and forced longitudinally through the conduit, past the baffle element 6, wherein a complete rotary intermixing occurs, and into the combustion chamber, where the mixture is ignited.

This burning is continued until the interior of the combustion chamber is in a state of incandescence, after which the liquid fuel is cut off and the solid fuel admitted. As 5 the pressure from the element 5 is comparatively slight, it is apparent that the banking of the solid fuel incident to the use of the conveyer 9, combined with the quantity of such solid material, will effectively resist 10 pressure through said feed pipe, with the result that the solid fuel will be fed through the unrestricted portion of the feed pipe in a solid stream, met by the pressure stream, and forced longitudinally of the 15 conduit, past the baffle element 6, and into the combustion chamber. In the movement of the solid fuel past the baffle element, it is, in the form of baffle element shown, given a rotary motion, and at the same time put 20 under more or less pressure, so that as it enters the combustion chamber, it will, by reason of these conditions, spread within said chamber for its most effective consumption under the incandescent condition of the 25 chamber. It is understood that the pressure from the element 5 is insufficient to force the fuel the full length of the combustion chamber, so that its consumption is assured within the body of the chamber. 30 The improved burner is designed for developing an extremely high degree of heat under ordinary conditions of fuel consumption, with the further effect of a more or less perfect consumption of solid fuel. The 35 use of the burner is contemplated in any and all places and under any and all condi-

tions where fuel consumption is utilized, it being particularly advantageous in steam generation.

What is claimed is:—

1. A burner including a combustion chamber, a conduit having communication with the chamber, a fluid pressure device opening into the conduit and directing the pressure longitudinally thereof toward the chamber, 40 a liquid fuel feed pipe opening into the conduit beyond the pressure device relative to the chamber, and a solid fuel feed pipe opening into the conduit between the pressure device and the chamber, said conduit 45 being open to the atmosphere beyond the liquid fuel feed pipe.

2. A burner including a combustion chamber, a conduit having communication with the chamber, a fluid pressure device opening 50 into the conduit and directing the pressure longitudinally thereof toward the chamber, a liquid fuel feed pipe opening into the conduit beyond the pressure device relative to the chamber, a solid fuel feed pipe opening 55 into the conduit between the pressure device and chamber, and an interrupter arranged in the conduit between the solid fuel feed pipe and the chamber, said conduit being open to the atmosphere beyond the liquid fuel 60 feed pipe.

In testimony whereof I affix my signature in presence of two witnesses.

CHARLES VIVION STUART.
